METHOD OF AND APPARATUS FOR RECOVERING FLUIDS FROM UNDERGROUND STRATA

Application filed November 10, 1931. Serial No. 574,118.

This invention relates to improvements in the art of withdrawing and recovering fluids such as mineral oil, from underground strata. More particularly, it relates to a method of cementing combination strings of casings within a well hole whereby a perforated or slotted screen pipe or casing may be positioned and properly cemented at or near the bottom of a well hole.

10 The invention also relates to means whereby proper circulation of mud fluid or other liquid may be obtained through the slotted or perforated pipe or casing.

Numerous methods of cementing casing in well holes have been evolved heretofore. Considerable difficulty, however, has been experienced in cementing a combination string of casing. By a combination string, reference is made to a casing containing or includ-

20 ing one or more lengths of slotted, perforated or other type of screen casing, such slotted or perforated screen being generally attached to the lower end of a string of imperforate casing of substantially the same diameter.

25 When such combined string is placed within a larger casing, the lower end of the combined string extending below the larger casing, and the string then cemented to the well hole below the large casing, such combined string may function as a combination string, oil passing through the central casing and water through the annular space between said central casing and the outer and larger casing. Heretofore, it has been difficult, if

30 not impossible, to place a screen pipe or casing in the bottom of a well hole and circulate water or a light mud fluid through such screen and combination string for the purpose of removing debris, detritus, cuttings and other material present in the bottom of a well hole.

This invention relates to a method by means of which it is possible to cement a casing in a well hole, the cementing action taking place slightly or immediately above the slotted or perforated casing.

45 Another object of this invention is to disclose and provide means whereby circulation of mud fluid may be carried out through a string of casing having a strainer therein.

Another object of this invention is to disclose and provide a strainer construction permitting circulation of a suitable fluid therethrough for a predetermined length of time.

50 Another object is to disclose and provide means whereby a well may be cemented at a point above slotted or perforated screen pipe or casing, without filling, obstructing or clogging the slots or perforations with the cementing material.

55 These and other objects, uses and advantages of this invention will be apprehended by those skilled in the art from the following detailed description of illustrative examples of this invention.

60 In describing the invention, reference will be had to the appended drawings, in which

Fig. 1 is a vertical section through the lower portion of a well hole.

65 Fig. 2 is an enlarged longitudinal section through a part of the screen casing shown in Fig. 1.

70 Fig. 3 is an enlarged longitudinal section through a part of screen casing prepared in accordance with this invention and adapted for use as in Fig. 1.

75 Fig. 4 is a vertical section through the lower portion of a well hole, illustrating one method and means employed in cementing the casing in said well hole.

80 Fig. 5 is a longitudinal section through a modified form of cementing valve adapted for use in this invention.

85 Fig. 6 illustrates the device shown in Fig. 5 in cementing position.

90 Fig. 1 illustrates a casing 2 cemented in the formation as indicated at 3. The casing 2 may have been cemented in any desired manner and the cement then drilled out to form the bore 4 and the well hole therebelow into a sand 5. The casing 2 may be one of several telescoping casings of progressively increasing size as these casings approach the surface of the ground. The central string which may be termed the oil string (in case the sand 5 contains mineral oil), may consist of imperforate casings 6 jointed together by couplings or collars 7 and a casing section 8 provided with a restriction or washer 9 restricting the cross sectional area of the casing 100.

at that point. Below the casing section 8 may be one or more strings of screen casing 10 provided with suitable apertures, slits or perforations 11. The screen casing 10 may 5 be connected to the casing section 8 in any suitable manner as, for example, by means of collars or couplings. A suitable guide shoe 12 may be carried by the lower end of the screen casing 10.

10 The use of perforated pipe or casing such as the section 10, is particularly advantageous in formations which are loose and shifting and which may readily cave in, thereby restricting or completely stopping the upward 15 flow of oil from the sand 5. It is to be understood that during the drilling of the well hole 4 into the sand 5, a considerable amount of debris, detritus, cuttings, etc., may accumulate in the bottom of the well hole 4. During 20 the withdrawal of the drilling tool and during and after the lowering of the oil string or combination string, sloughing may occur, partially filling the bottom of the well hole 4. For this reason, it is highly desirable 25 to be able to maintain a circulation of mud fluid or other liquid through the entire length of the combination string 6 and through the annular space surrounding the string.

Heretofore it has been impossible to circulate 30 late through a combination string so as to cause the light mud fluid to be discharged from the bottom end of the string and be circulated upwardly through the well hole outside the screen to thoroughly wash and remove 35 cavings outside the screen. In normal practice, the fluid being pumped into the well is discharged through the perforations 11 of the screen or perforated casing, thus preventing the possibility of washing out the bottom of the well hole and removing the debris accumulated therein. In accordance 40 with this invention, however, the perforations or openings 11 of the screen casing or pipe, are filled or closed with a substance 45 capable of being removed either by the action of heat, pressure, the removal of a closure by drilling or disintegration, or by the continued action of water. A positive circulation may thus be established through the end 50 of the screen and throughout the outside of the screen and casing, without the use of complex packers or other devices.

In other words, the perforations 11 of the screen casing may be filled or closed with a 55 substance which will effectively plug or close such openings until circulation has been carried out. Thereafter the substance employed in plugging the perforations in the screen casing may be removed.

60 Illustrative of this phase of my invention, reference is made to Fig. 2 wherein the slotted casing 10 provided with apertures 11 is shown provided with a filling material 13 in such openings or perforations 11. The 65 substance used in sealing the openings 11

may be either removable by the continued action of water, by the action of heat, or in any other suitable manner without withdrawing the screen casing from the well hole.

For example, the openings or perforations 70 11 may be filled with a sulfur compound in molten form. In preparing the string of perforated casing, the molten sulfur composition may be applied internally and/or externally of the slotted pipe or screen casing 75 while such compound is in liquid form, and allowed to congeal or set within the various perforations 11, or the string may be mounted in a suitable chuck and spun on its longitudinal axis, the sulfur compound being introduced into the spinning casing in liquid 80 form and distributed by centrifugal action into the various perforations 11.

During such spinning, the exterior of the 85 perforated string may be wrapped with heavy paper or the like, to maintain the sulfur compound within the apertures 11. After spinning and after the sulfur compound has completely filled and set within the openings 11, the paper may be removed and the 90 perforated casing lowered into the well hole.

After being lowered into the bottom of the well hole or into contact with the accumulated detritus at the bottom, the fluid being circulated through the string will be discharged 95 from the lower end of the casing and not through the openings or perforations 11 inasmuch as such perforations or openings are sealed with the sulfur compound. After the string has reached the true bottom of the 100 well hole or the position in which it is desired to maintain such screen pipe or casing, hot water may be admitted through the casing so as to soften, melt and remove the sulfur compound from the openings 11, thereby 105 restoring the slotted or perforated casing to its original condition.

Instead of employing a sulfur compound or other similar composition capable of being melted and removed from the apertures 11 by the action of heat, the openings 11 may be filled with a plastic composition containing ground bentonite, barytes, etc. and the inner surface of the screen pipe or casing coated with a layer of cementitious material capable of setting and maintaining its strength 110 for a desired time and also capable of disintegrating under the continued action of water. A cementitious composition answering these requirements may be made by mixing 115 Portland cement with a solution containing a crystallizable salt in sufficient quantity to prevent a major portion of the cement particles from hydrating in bonding contact with each other. For example, if Portland cement is mixed with a relatively small amount of water containing a high proportion of calcium chloride, the resulting mixture will set but calcium chloride crystals 120 will form throughout the mass, these crystals 125

forming what may be termed "parting planes", separating individual particles of Portland cement. The set mass will exhibit a considerable amount of strength or at least sufficient strength to withstand the pressure of fluid being pumped through a perforate casing lined with such composition, for an appreciable length of time. Under the continued action of water, however, the calcium chloride will be dissolved in the water passing through the casing lined with said composition, and the cementitious coating will eventually disintegrate and be washed away.

15 It will thus be seen that a casing lined with a cementitious composition of the character described hereinabove, such as for example the casing 10 lined with the cementitious composition 14 shown in Fig. 2, may be attached to the lower end of an oil string and circulation of fluid may be established through such prepared perforate casing for an appreciable length of time before the cementitious coating 14 will disintegrate and permit the fluid to pass through the apertures 11. By properly proportioning cement, calcium chloride and water, the resulting cementitious mixture may be caused to withstand the pressure of the circulating fluid for any desired time interval, say 12 hours, 24 hours, 48 hours, etc.

Instead of employing calcium chloride, any other crystallizable salt solution may be employed. For example, I have found that suitable cementitious compositions capable of being used as a lining or filling for perforate casing may be made by employing compositions consisting of Portland cement and molasses or sugar solutions. During the setting of the cementitious composition, sugar crystals are formed between the particles of Portland cement so that the dried cementitious mass exhibits considerable strength. When such cementitious composition is exposed to the action of water, however, the water soluble crystals of sugar go into solution in the water, thereby causing a partial disintegration of the cementitious body. Water soluble salts of high water of crystallization content such as aluminum sulfate, iron sulfate, the various alums, calcium phosphate, sodium phosphate, citrate, sulfate and tetraborate and others, are adapted for use in cementitious compositions of the character described hereinabove.

It is not necessary that the cementitious body or lining placed upon the inner surfaces of the perforate pipe or casing be completely removed by the action of the fluid circulated through the casing; it is merely sufficient that the continued circulation will in time so weaken or partially disintegrate the body that it may be readily removed subsequently by a suitable tool lowered into the casing.

65 Illustrative of the compositions which may

be employed in sealing the openings in the perforate pipe or casing, it may be said that a compound consisting of 100 parts of cement, 6 parts of calcium chloride, 50 parts of sugar and 40 parts of water, results in a cementitious body capable of setting and drying without the formation of cracks and in effectively sealing the apertures in a slotted, perforated or other screen pipe or casing. This composition will be substantially disintegrated when water is passed through the casing under pressure for a period of about one hour. By decreasing the amount of sugar or by increasing the amount of cement, the time interval during which water may be passed through the casing without being discharged through the apertures of said casing, may be materially increased.

Another method of temporarily sealing the openings in perforated or screen pipe or casing which may be employed to advantage, comprises the application of a thin layer of sodium silicate to the interior surfaces and perforations of the screen casing. The coated interior surface of the screen casing may then be provided with a thin coat of cementitious material such as, for example, a neat Portland cement grout. The sodium silicate coating is preferably allowed to set before the Portland cement liner is formed within the casing. When a casing prepared as described hereinabove is then used in a combination string, it will be found that the fluid passing through the casing will eventually soften and dissolve the sodium silicate, permitting the entire central lining of Portland cement to separate from the wall and slough off to the bottom of the hole. Or such inner liner of cement may be subsequently removed by a drilling tool lowered through the casing.

Those skilled in the art will apprehend that wherever reference is made herein to a cementitious composition, such reference embraces not only compositions containing hydraulic cement, but other compositions as well, capable of setting or drying to form a body adapted to withstand the action of fluid for an appreciable length of time. Such compositions may be composed of sulfur, either alone or in combination with mineral fillers, or these compositions may be made from various hydrocarbons and pyrobitumens such as gilsonite, asphalt, etc.

Hydrocarbon compositions preferably include finely divided mineral fillers and reinforcing agents such as diatomaceous earth, magnesium carbonate, sulfur in finely divided condition, asbestos, etc., as the presence of such fillers and reinforcing agents tends to raise the melting point of the resulting composition. In addition, fusible metallic compounds and alloys may be employed such as, for example, Darcel's metal, Newton's metal, etc., instead of the cementitious compositions

- mentioned hereinabove. An alloy comprising 25% of tin, 25% of lead and 50% of bismuth, has a melting point of about 93° C. An alloy containing 35% of tin, 45% of lead and 20% of bismuth, has a melting point of about 150° C. Numerous metallic compositions having relatively low melting points are known and such metallic compounds may be applied to the perforations of the
- 10 screen pipe or casing before such casing is lowered into the well hole so as to permit circulation of fluid through the end of the screen, and after such circulation has removed the debris and permitted the casing
- 15 to be properly positioned in the well hole, such fusible metal may be readily removed from the perforations by a suitable application of heat to the screen as, for example, by steam injection.
- 20 The following method of preparing screen pipe or casing, illustrated in Fig. 3, has been found to be particularly effective and economical: A tough, parchment-like oiled paper 20 (such as stencil paper about 0.006 inches
- 25 thick) is inserted into the screen pipe 10 to form an inner liner. Two thicknesses of stencil-type paper are desirable. A volume of cement slurry is then introduced into the lined screen, plugs inserted in the ends and
- 30 the screen is spun for a desired length of time until a layer of cement 21 is formed on the interior. During spinning, some water may be thrown off through the paper and openings in the screen. The finished screen, therefore,
- 35 comprises an inner layer of cement separated from the screen pipe by a layer of fibrous material. This or any other prepared screen casing is then attached to the imperforate casing and valved casing section and
- 40 lowered into the well.
- It may be desirable not to seal all of the perforations or openings of the screen pipe or casing by a composition of the character described hereinabove. As shown in Fig. 1,
- 45 all of the apertures 11 in the screen casing 10 may be so sealed but perforations 15 near the bottom end of such casing may be left open so as to permit a certain amount of fluid being passed down through the combination
- 50 string to be discharged through such openings 15, thereby facilitating somewhat the removal of debris and the establishment of proper circulation in the bottom of the well hole. The fluid passed through the prepared screen pipe or casing may be a relatively thin mud fluid.
- As shown in Fig. 1, the casing section 8, substantially of the same internal diameter as the casing 6, is provided with a plurality
- 60 of valve members 16 inserted through a plurality of apertures formed in the casing section 8. These apertures are provided with walls which flare outwardly and the valve members 16 are wedged in such apertures and
- 65 extend inwardly toward the center of the

casing section. The valve members 16 may be made of wood, cast iron, or other brittle, easily sheared substance. The valve members 16, furthermore, are positioned above the retaining ring or restriction 9 carried by the

70 casing section 8.

The various elements described hereinabove may be utilized in the following manner:

The casing or cementing section 8 may be attached to the upper end of screen casing 10 and imperforate casing 6 may be attached to the upper end of the cementing device 8. The screen casing may be prepared as has been described hereinabove, the apertures in said screen being sealed off by means of a suitable composition or liner. The assembled casing is then lowered into the well hole. Circulation of mud fluid is established downwardly through the casing and screen and upwardly through the annular space separating the screen and casing from the walls of the well hole. Such circulation is preferably maintained until all debris, cavings, etc., are removed from the well hole so that a mud fluid of substantially uniform gravity exists within the casing and in the annular space surrounding the same. In order to cement the casing in the well hole at a point immediately above the screen, a plug known as a bottom

80 plug 17 is inserted into the top of the casing on top of the mud fluid existing therein. A proper amount of cement slurry is then introduced on top of the plug 17 and such cement slurry pumped into the casing, forcing mud

85 fluid from the casing through the bottom of the screen. The plug 17 is preferably made of wood or other easily destroyed material and should be of a size slightly smaller than the interior diameter of the casing. It may be provided at its upper end with a flexible gasket 18.

The plug 17 and the cement slurry thereabove is forced downwardly through the casing 6 and finally comes in contact with the inwardly extending ends of the valve members 16. Under the influence of pressure of the cement slurry, the plug 17 breaks off the inwardly extending ends of the valve member 16 and comes to rest upon the restriction 9 carried by the cementing casing section 8. The plug 17 then occupies a position between the restriction 9 and the ports 19 in which the valves 16 have been held.

A second plug known as the top plug, is then introduced into the casing on top of the cement slurry. This top plug may be provided with a measuring line. A suitable hydraulic fluid is then introduced into the casing on top of the top plug and the top plug forced downwardly through the casing, forcing the cement slurry below said top plug out through the ports 19. The valve members 16, formerly retained in said ports, are blown out by the head of cement slurry and

100

105

110

115

120

125

130

the pressure with which said cement is being forced into the casing. Inasmuch as the lower end of the well hole is filled with a quiescent mud fluid, the cement slurry ejected 5 through the ports 19 follows the line of least resistance and moves upwardly through the annular space between the casing 6 and the well hole.

It has been found that the cement slurry 10 will not settle downwardly below the ports 19 for any appreciable distance, the cement slurry being supported by the non-compressible and quiescent mud fluid remaining in the bottom of the well hole. By observing the 15 measuring line attached to the top plug, the application of pressure may be stopped when the top plug is within a certain predetermined distance of the bottom plug 17, thus causing a predetermined thickness of cement to set 20 within the casing 6.

Instead of employing a measuring line, a spacer may have been introduced into the cement slurry immediately beneath the top plug. The cementitious slurry sets exteriorly 25 of the casing 6 supported by and suspended above the screen pipe, effectively cementing the casing to the well hole above the screen and thus preventing water or other material from points above the screen 5 from passing 30 down into the screen casing.

In the event that some settling or grading of the cement slurry may occur slightly below the ports 19, there is no possibility of having the cement plug up the apertures in 35 the screen as such apertures have been closed with a sealing means.

After a suitable time interval has elapsed and the cement slurry has set, drilling tools 40 may be lowered through the casing and cement remaining in the casing drilled out. The drilling also destroys and removes the plug 17 as well as the stop 9. The debris thus created may be washed and bailed out until all of the débris as well as most of the mud 45 fluid remaining in the screen casing 10 is removed.

By the time the drilling tools pass through the top plug, cement and bottom plug 17, the cementitious coating on the interior surfaces 50 of the screen pipe 10 has disintegrated so that it may be readily and quickly removed by the drilling tool without incurring the possibility of unscrewing the screen casing from the upper portion of the combination 55 string. Or the drilling tool may be lowered into the screen and the inner seal removed. The screen may be spot welded to the adjoining casing to prevent the screen from being unscrewed from the casing. If a fusible sealing means has been used on the screen casing 10, then hot water may be passed through the wash-out tube so as to reduce the fusible sealing substance to liquid form and thus permit the removal of such substance by 60 bailing or circulation.

Instead of employing the cementing casing section 8 illustrated in Figs. 1 and 4, a cementing section such as is shown in Figs. 5 and 6 may be used. As shown in these drawings, the cementing device consists of a tubular member 22 which may be made from ordinary tubular collar or coupling stock. The member 22 may be internally threaded at either end so as to threadedly engage with an imperforate casing 6 at one end and a 70 screen casing 10 at the other end. The body portion of the device may be provided with a plurality of peripherally spaced outwardly flaring ports 23. Valve means may be provided for normally keeping these ports closed. 75 For example, poppet valve members 24 adapted to seat in the ports 23 may be held in such ports by means of spring members 25 attached to the body portion 22 in any suitable manner as, for example, by means of 80 machine screws 26.

A sleeve 27 may be slidably carried within the tubular member 22. Such sleeve 27 may be provided with an inwardly extending stop of any suitable character. For example, a stop such as 9 in Figs. 1 and 4 may be carried by the sleeve 27. As shown in Figs. 5 and 6, however, the sleeve 27 is provided with a back pressure valve having a body portion 28 of cement, aluminum or 90 other readily destroyed material, but of sufficient strength to withstand the service required.

Means for retaining the sleeve 27 within the body portion 22 of the device in position 100 to cover the ports 23, may be provided. The sleeve 27 may be provided with a peripheral groove and the interior surface of the tubular member 22 provided with an inwardly extending bead as shown at 31. The inner sleeve 105 27 may then be pressed into the tubular member 22 during assembly until the bead 27 on the interior surface of the tubular member 22 engages with the groove of the sleeve 27. The force required to release the friction hold 110 thus made may be regulated and noted during assembly. When in such engaged position, the upper end of the sleeve 27 is preferably in substantial abutting relation with the end of the casing 6 threadedly connected 115 to the upper end of the tubular member 22. The bead and groove means here described not only function as a releasable means holding the sleeve in position over the ports 23 but in addition function as a seal preventing 120 fluid from passing into the well hole.

Instead of the bead and groove friction hold, shear pins such as the pin 30 may connect the sleeve 27 with the tubular body portion 22 of the device. When thus connected, 125 as shown in Fig. 5, the ports 23 are closed by the upper end of the sleeve 27.

Means may be provided for preventing rotation of the sleeve 27 within the tubular body portion 22 of the device. Such means 130

may comprise a pin 32 carried by the body portion 22 and extending inwardly and adapted to be slidably received in a longitudinal slot 33 in the lower end of the member 27, said pin 32 being adapted to enter and cooperate with the slot 33 when the sleeve 27 is moved downwardly so as to expose the ports 23.

After the string has been assembled, said 10 string including the prepared perforated casing 10, the cementing device and the imperforate casing 6, and such string lowered into the bottom of the well hole, circulation is maintained as described hereinabove until 15 the entire well hole including the space surrounding the screen has been cleared of all débris and all cavings, bridges, etc., removed. A bottom plug 17' is then inserted into the top of the casing on top of the mud fluid 20 therein, this plug being of such size that it will pass down through the casing but will not pass through the stop or restriction carried by the sleeve 27 of the casing device. The bottom plug 17' may be provided with a 25 suitable expanding gasket 18'. A suitable charge of cement slurry is introduced into the casing on top of the plug and such cement slurry forced downwardly into the casing advancing the bottom plug 17' and displacing 30 mud fluid in the string. A top plug is inserted into the casing on top of the charge of cement, such top plug being followed by a suitable hydraulic fluid introduced to give sufficient pressure to force the cement slurry 35 and bottom plug into contact with the restriction, stop or back pressure valve carried by the sleeve 27. A sufficient pressure is built up within the casing 6 to cause the sleeve 27 to move downwardly and to release the friction hold between the sleeve 27 40 and the body portion 22 of the cementing device. Downward motion of the sleeve 27 uncovers the ports 23 and the cement slurry is then forced outwardly through the ports 23 45 into the annular space surrounding the cementing device and casing. As described hereinabove, the cement slurry rises upwardly in the annular space surrounding the casing 6. A sufficient quantity of cement slurry 50 is allowed to remain within the casing 6 above the bottom plug 17' so that if any dilution or grading of the top portion of the cement slurry has occurred, all such diluted or graded slurry will remain within the casing. 55

If instead of the friction hold including the bead and groove construction described hereinabove, shear pins 30 have been used as the releasable means, the pressure of the 60 cement slurry is sufficient to shear the pins 30 and move the sleeve 27 downwardly, thus uncovering the ports 23. The downward movement of the sleeve 27 causes the pin 32 carried by the body portion 22 to engage 65 with the slot 33 of the sleeve 27.

After the cement has set, any cement that may have been left in the casing is drilled out together with the two cementing plugs and the stop or back pressure valve carried by the sleeve 27. Rotation of the sleeve 27 70 within the body portion 22 is prevented during this drilling operation by the pin 32. The lining or cement within the screen casing 10 may also be drilled out leaving the perforations of the screen open to the producing 75 formation.

It will be understood that the slidable sleeve 27 instead of completely uncovering the ports 23 may be provided with similar ports which are in offset relation when the 80 sleeve 27 is in locked position within the tubular body portion 22 and in aligned position with the ports 23 when the friction hold or shear pins are released.

It will be apparent to those skilled in the 85 art that a novel method of preparing screen pipe or casing has been disclosed whereby it is possible to circulate a fluid through a screen pipe or casing while restricting the 90 flow of fluid through the perforations of such 95 screen. Positive circulation of mud fluid completely around the screen casing is insured.

Furthermore, those skilled in the art will apprehend the advantageous simplicity of 95 the elements described hereinabove for cementing a casing within a well hole. The use of complicated devices such as packers, wash pipes, etc., is obviated. It is to be noted that the cementing device has an interior diameter equivalent to the interior diameter of 100 the casing itself, thereby not impairing the effective area of the string. Moreover, the method of cementing is novel in that the cement slurry is supported and suspended exteriorly of the casing upon a quiescent body 105 of mud fluid.

Although specific embodiments of the invention have been described in detail, it will 110 be apparent that numerous changes and modifications may be made without departing from the scope of this invention.

All such changes and modifications as come 115 within the scope of the appended claims are 115 embraced thereby.

I claim:

1. In a method of cementing a combination string within a well hole, the steps of sealing apertures in a screen casing, lowering 120 a string of imperforate casing to which said sealed screen casing is attached into a well hole, circulating a fluid through said combination string, plugging the string above said sealed screen casing, opening passageways in the casing above the point at which it was plugged, admitting a cementitious material from said casing and passageways into the well hole, permitting said cementitious material to set, and then clearing the center 125 130

- of said casing and opening the apertures in said screen.
2. In a method of cementing a combination string within a well hole, the steps of sealing apertures in a screen casing, lowering a string of imperforate casing to which said sealed screen casing is attached into a well hole, circulating a fluid through said combination string and upwardly outside of said screen casing and imperforate casing, inserting a plug into the top of the casing, introducing a cement slurry on top of said plug, introducing a top plug on top of said cement slurry, introducing and forcing a hydraulic fluid into the casing on top of said top plug to cause said bottom plug to open passageways in said combination string at a point above said screen, forcing the cement slurry through said passageways and upwardly around said imperforate casing, allowing said cement slurry to set, and then clearing the center of said casing and opening the apertures in said screen.
3. In a method of cementing a combination string within a well hole, the steps of sealing apertures in a screen casing, lowering a string of imperforate casing to which said sealed screen casing is attached into a well hole, circulating a fluid through said combination string, plugging the string above said sealed screen casing, opening passageways in the casing above the point at which it was plugged, admitting a cementitious material from said casing and passageways into the well hole, and permitting said cementitious material to set.
4. In a method of cementing a combination string within a well hole, the steps of sealing apertures in a screen casing, lowering a string of imperforate casing to which said sealed screen casing is attached into a well hole, circulating a mud fluid through said combination string and upwardly around said screen casing, plugging the string above said sealed screen casing, opening passageways in the casing above said screen casing, forcing a cementitious material into said casing and through said passageways into the well hole and upwardly around said imperforate casing in said well hole, and permitting said cementitious material to set.
5. In a method of cementing a combination string within a well hole, the steps of sealing apertures in a screen casing, lowering a string of imperforate casing to which said sealed screen casing is attached into a well hole, circulating a mud fluid through said combination string and upwardly around said screen casing, plugging the string above said sealed screen casing, opening passageways in the casing above said screen casing, forcing a cementitious material into said casing and through said passageways into the well hole and upwardly around said imperforate casing in said well hole, comprising the steps of sealing apertures in a screen casing with a fusible material, lowering the sealed screen casing into a well hole, and then opening the apertures in said screen while in said well hole by the application of heat.
6. A method of the character described comprising the steps of sealing apertures in a screen casing, lowering the screen casing into a well hole, circulating fluid through said screen casing in said well hole, and opening the apertures in said screen casing while in said well hole.
7. In a method of setting screen pipe and casing in a well hole, the steps of lowering a screen pipe into a well hole, and circulating fluid downwardly through the center of said screen pipe and upwardly through the well hole around said screen pipe while restricting the flow of fluid through perforations in said screen.
8. In a method of setting screen pipe and casing in a well hole, the steps of sealing the apertures in a screen pipe, lowering the screen pipe into a well hole, circulating fluid downwardly through the center of said screen pipe and upwardly through the well hole around said screen pipe to clear the well hole around said screen pipe, and then opening the apertures in said screen pipe while in said well hole.
9. In a method of setting screen pipe and casing in a well hole, the steps of applying a layer of cementitious material to the interior surfaces of a screen pipe, attaching said screen pipe to imperforate casing, lowering a string of imperforate casing to which said sealed screen pipe is attached into a well hole, circulating fluid downwardly through the center of said screen pipe and upwardly through the well hole around said screen pipe to clear the well hole surrounding said screen pipe, and then drilling out the internal layer of cementitious material on said screen pipe while preventing relative rotation of said screen pipe and casing.
10. A method of setting screen casing in a well hole, comprising the steps of sealing apertures in a screen casing with a fusible material, lowering the sealed screen casing into a well hole, and then opening the apertures in said screen while in said well hole by the application of heat.
11. In a method of setting screen casing in a well hole, the steps of sealing apertures in a screen casing with a cementitious composition adapted to disintegrate under the continued action of aqueous liquid, lowering the sealed screen casing into a well hole, and circulating fluid through said screen casing in said well hole.
12. A screen casing provided with a plurality of apertures in the walls thereof, and a removable sealing means adjacent the interior surface of the screen casing, said sealing means being adapted to restrict flow of fluid through said apertures.

13. A screen casing provided with a plurality of apertures therein, and a filler of sealing material in said apertures, said sealing material being adapted to disintegrate under continued contact with an aqueous fluid. 70
14. A screen casing comprising a casing provided with a plurality of apertures therein, and a lining of cementitious material on the inner surfaces of said screen casing, said cementitious material being adapted to retard the flow of fluid through said apertures for a predetermined period of time and to weaken and partially disintegrate by continued contact with an aqueous fluid. 75
15. A screen casing provided with a plurality of apertures in the walls thereof, and provided with a fusible sealing means adapted to retard flow of fluid through said apertures and to melt and open said apertures under action of heat. 80
16. A screen casing provided with a plurality of apertures in the walls thereof, said casing being provided with a lining of cementitious material on the inner surfaces, said cementitious material being adapted to retard flow of fluid through said apertures for a predetermined period of time. 85
17. A screen casing provided with a plurality of apertures in the walls thereof, and a lining of cementitious composition containing hydraulic cement and a water soluble crystallizable salt, a major proportion of particles of hydraulic cement in said composition being separated from each other by said salt in crystallized form, said cementitious composition retarding the flow of fluid through said apertures. 90
18. A screen casing comprising a casing provided with a plurality of apertures therein, and a destructible, coherent lining of cementitious material on the inner surfaces of said screen casing, said lining being adapted to retard the passage of water through the apertures. 95
19. A screen casing provided with an inner destructible, coherent lining of cementitious material, and a fibrous material between said lining and said casing, said lining being adapted to retard the passage of water through said screen casing. 100
20. A string of casing comprising a tubular cementing device provided with internally threaded end portions, an imperforate casing threadedly connected to one end of said device and a screen casing, provided with a removable sealing means in its apertures, threadedly connected to the other end of said device, said cementing device including a tubular body portion, a plurality of outwardly flaring ports in the walls thereof, valve members in said ports and extending inwardly of said body portion, said valve members being adapted to be sheared off by application of force longitudinally of said 110
